UNITED STATES PATENT OFFICE.

JAMES D. MINTO AND JAMES KELLY, OF PROVIDENCE, RHODE ISLAND
AIR COOLING AND HUMIDIFYING APPARATUS.

No. 855,719.

Specification of Letters Patent.

Patented June 4, 1907.

Application filed April 3, 1906. Serial No. 309,681.

To all whom it may concern:

Be it known that we, JAMES D. MINTO and JAMES KELLY, citizens of the United States, residing at the city of Providence, in the county of Providence and State of Rhode Island, have invented certain new and useful Improvements in Air Cooling and Humidifying Apparatus, of which the following is a specification.

This invention relates to certain new and useful improvements in air cooling and humidifying apparatus and is an improvement in the type of such devices as is shown and claimed in prior patent No. 787,454 issued April 18, 1905, and also the type shown and described in application filed by James Kelly September 15, 1905, Serial No. 278,651.

The present invention has for its object to provide a device or apparatus of the character stated by means of which a perfect discharge of either a hot or cold vapor from the distributor or atomizer may be effected.

A further object of the present invention is to provide a device in which the drip-pipes ordinarily employed in devices for the same purpose, are entirely dispensed with, and in which the supply pipes utilized may be of much smaller diameter than is required with the majority of devices employed for similar purposes.

A still further object of the present invention is to provide a device in which a constant supply of pure water is assured, as well as a constant supply of fresh air, and in which the supply may be readily and easily regulated and controlled as desired.

The device forming the subject matter of this application is adapted for cooling the air of apartments and buildings, and is especially adapted for the rooms of mills having textile machinery, as in such rooms, the air is liable to become very dry or full of dust of fibers in consequence of the operation of the machinery or the employment of manufacturing processes, which are detrimental to the health or comfort of the workmen, and while the device is particularly adapted and designed for such use, it is equally adapted for use in other relations, such for instances as in hospitals and the like.

In the accompanying drawings forming a part of this application, we show a practical embodiment of the invention as it has been practiced by us, and in the following descrip-

tion, will have reference thereto, like letters 55 indicating like parts throughout the different views, it being understood however, that while a practical and preferable embodiment of the invention is shown and will be described, we do not desire to limit ourselves to 60 specific details of construction shown.

In the said drawings: Figure 1, is a perspective view of an air cooling and humidifying apparatus constructed in accordance with our invention, diagrammatically illustrating 65 the manner in which same is arranged in a room or apartment. Fig. 2, is an enlarged central vertical sectional view of the distributor or atomizer. Fig. 3, is a cross sectional view thereof, taken on the line $x-x$ of Fig. 2. 70 Fig. 4, is a similar view taken on the line $y-y$ of Fig. 2.

As heretofore stated, we aim in the present invention to obviate the use of all drip pipes which are exceedingly objectionable in 75 mills and the like, as they interfere with the machinery, belting etc., especially if the ceiling is low, and again, it is important and essential in most mills that as little space as possible be occupied by subsidiary devices 80 such as humidifiers, the available space being required for the perfect working of the machinery.

We have designated the showing in Fig. 1, as a diagrammatical one, it being understood 85 that the blower A , is located at any desirable or convenient point, and being of a conventional form having the usual air-inlet b , air-chamber c , and relief-valve d . Communicating with the air-chamber c , is a pipe e , 90 which is extended upwardly and connected to the air-pipe e' , which in practice is generally located near to the ceiling, and approximately centrally of the room, and has connected thereto a branch e^2 , which carries 95 or is in communication with the improved vapor-distributer or atomizer f . g , is a pipe adapted to receive hot or cold water under pressure, and this pipe is also generally located close to the ceiling, substantially parallel with the air-pipe e' as shown. This pipe g , communicates through branches g' , g^2 , with the air-pipe, the branches g^2 , and e^2 of said pipes being connected at point h , generally by a three-way union or coupling 100 as shown. In the water-pipe, we also provide a water-valve i , generally located at the juncture of the branches g' , g^2 as shown.

The air-pipe is provided with a shut-off cock j , and the water-pipe is provided with a similar shut-off cock j' , and these are generally located in the branches g' , and e' of said pipes respectively. These cocks are opened and closed simultaneously by means of links connecting them, and a hand-operating rod k as shown, or other equivalent means. It is to be understood that we do not limit ourselves to the specific arrangement of the pipes as shown and described, or to the location of the shut-off cocks, as this may be altered at will to suit the conditions of the room in which the device is erected, without in any manner departing from the scope or spirit of the invention.

The vapor-distributer or vaporizer f comprises two members f' and f^2 , as shown in Fig. 2'. The upper member f^2 threads into, or is otherwise suitably joined to the depending branch of the coupling or union h . This member f^2 , is provided approximately midway of its length with an interior or internal nut f^3 , provided with one or more ports or passage-ways f^4 for the passage of the liquid-moisture. The lower member f' is provided with a stem f^5 which threads into said internal-nut f^3 of the member f^2 , so that the said members f' , and f^2 are thereby adjustably-connected together, and regulation of the discharge of vapor from the vaporizer or vapor-distributer is thereby readily effected.

The member f' of the vapor-distributer or atomizer is concaved on the upper face of its head, around the stem f^5 , substantially forming an annular valve-member f^6 around the perimeter of said head, which valve-member co-acts with the annular valve-member f^7 on the lower face of the head or lower end of the member f^2 . By turning the member f' toward or away from the member f^2 , it will be readily seen that the space between the two annular valve-members or faces is increased or decreased and the discharge of the vapor correspondingly increased or diminished.

The member f' has its bottom closed, and by this construction a receptacle f^8 is formed, said receptacle adapted to receive any of the liquid which has for any reason not become subjected to the atomizing process.

The operation of the device will, it is believed, be clearly evident to those skilled in the art, from the foregoing description, taken in connection with the accompanying drawings, as it will be evident that the air passing through air-pipe e' and the water passing through pipe g are brought together and commingled at point h , and discharged in the form of a spray through the vapor-distributer or atomizer f , the discharge of this spray being controlled as afore described by the adjustment of the lower member f' of the

distributer or atomizer f . We desire however, to call attention to the fact that in this device, we draw a constant supply of fresh air from the outside of the room in which the distributer or atomizer is located, which, combined with the fresh water, effects the best results obtainable, and by regulating the water supply, the spray can be made either heavy or fine as may be desired for the conditions existing in the room. It is to be observed also, that with the construction shown and described it is impossible for any foreign particles or matter with which the air in the mill-room may be charged to get into the air-pipe or water-pipe, and thus hinder the proper working of the device. By the employment of two valves, it is to be observed that we set one to regulate the supply as desired, and employ the other to shut off the atomizer when not in use. The chamber f^8 in the member f' of the distributer or vaporizer serves to catch any liquid that may not be discharged in the form of spray, and this drip-cup may be readily drained by removing the member f' when desired or necessary.

Having fully described our invention, what we claim as new and desire to secure by Letters Patent is:—

1. In a humidifying apparatus, an air supply and a communicating water supply, means for controlling said air supply and water supply, a distributer communicating with both the air supply and the water supply, comprising two members disposed in longitudinal alignment and with their adjacent faces slightly spaced apart and one of said members having a screw-threaded projecting shank adapted to engage a perforated nut in the interior of the other of said members substantially as described.

2. The combination with a water and air supply, of an atomizer comprising two tubular members, having enlarged contiguous ends with opposed slightly separated faces, one of said members having its one end closed and its other end perforated and provided with a bevel face, a screw-threaded shank projecting centrally from said bevel face, a perforated nut carried by the interior of the other of said members, said screw-threaded shank adapted to engage with said perforated nut, thereby forming means by which the two members of said atomizer are adjustably secured together.

In testimony whereof we affix our signatures in presence of two witnesses.

JAMES D. MINTO.
JAMES KELLY.
